TWO-STORY KNOCKDOWN VARIETY
DOLL HOUSELeni K. Hammond and Richard H. Stout,
Winnetka, Ill.

Application October 2, 1946, Serial No. 760,816

1 Claim. (Cl. 46—21)

1 The present invention relates generally to doll houses. More particularly the invention relates to that type of doll house which simulates a multi-room two story house with a gable roof, has the front thereof open in order that dolls and pieces of miniature furniture may be inserted into and removed from the rooms and is of knockdown construction or design so that it may be readily transported as well as stored.

One object of the invention is to provide a doll house of this type which is generally of new and improved construction and is characterized by the fact that it may be produced at a comparatively low cost and when dismantled occupies but a comparatively small space.

Another object of the invention is to provide a doll house of the type under consideration which comprises in addition to a gable roof and a pair of triangular gable forming members, a pair of open front rectangular or box-like room forming units which are adapted to be positioned in side by side relation and to form the first story of the house, and a pair of open front rectangular or box-like units which are adapted when the house is properly assembled to overlie and rest on the first story units and form a pair of spaced apart outside second story rooms for the house.

Another object of the invention is to provide a doll house of the last mentioned character in which the four room forming units are so proportioned so far as width and height are concerned that they all may be nested for transportation or storage purposes while at the same time when the house is in proper assembled relation the ceiling forming walls of the two first story units are coplanar and the ceiling forming walls of the two second story units are coplanar to the end that the house as a whole is symmetrical and it is possible to make the triangular gable forming members the same in size.

Another object of the invention is to provide a doll house of the type and character last mentioned in which both of the first story units are the same in height, one of the first story units is of sufficiently less width than the other first story unit that when it is turned at right angles to the other unit it may be nested into the latter, one of the second story units is of the same width as the smaller sized first story unit but is of sufficiently less height that by turning it at right angles to the smaller sized first story unit it may be nested into the latter, and the other second story unit is the same in height as the one second story unit but is so proportioned that it may be nested into said other second story unit by

turning it at right angles relatively to the latter.

5 A further object of the invention is to provide a doll house of the type and character under consideration which comprises in addition to the parts heretofore mentioned a fifth open front rectangular or box-like room forming unit which is adapted to be interposed and form a room between the two main or primary second story units and is so proportioned that it may be nested into

10 the narrower of the latter units.

A still further object of the invention is to provide a doll house of the aforementioned type or character in which the gable roof is formed of four rectangular sections which are hinged together in order that the roof may be folded lengthwise and crosswise into a unit of such size that it may be stored or disposed in one of the room forming units when the house is in dismantled form.

20 Other objects of the invention and the various advantages and characteristics of the present doll house will be apparent from a consideration of the following detailed description.

The invention consists in the several novel 25 features which are hereinafter set forth and are more particularly defined by the claim at the conclusion hereof.

In the drawings which accompany and form a part of this specification or disclosure and in 30 which like numerals of reference denote corresponding parts throughout the several views:

Figure 1 is a perspective showing in assembled form a doll house embodying the invention, a portion of the gable roof being broken away in order to show or illustrate the construction and design of the gable forming members;

Figure 2 is a vertical longitudinal section of the house showing the manner in which the first story and second story units are arranged in side by 35 side relation when the house is assembled;

Figure 3 is a perspective of one of the gable forming members;

Figure 4 is a front view showing the fifth room 45 forming unit, i. e., the unit that is adapted to be interposed and form a room between the two main second story units, nested in the smaller sized main second story unit;

Figure 5 is a front view showing the smaller sized main second story unit with the fifth room forming unit therein turned at right angles to and nested in the larger main second story unit;

Figure 6 is a front view showing the larger sized main second story unit turned at right angles to and nested in the smaller sized first story unit;

Figure 7 is a front view showing the smaller

sized first story unit with the second story units therein turned at right angles to and nested in the larger sized first story unit;

Figure 8 is a perspective showing the roof in partially folded form; and

Figure 9 is a horizontal section taken on the line 9—9 of Figure 7 and illustrating the various component parts of the doll house in their dismantled or nested form.

The doll house which is shown in the drawings constitutes the preferred form or embodiment of the invention. It is essentially of the knock-down type or variety and as its component parts comprises a pair of first story units 10 and 11, three second story units 12, 13 and 14, a pair of gable forming members 15 and a gable roof 16. When these parts are properly assembled as shown in Figures 1 and 2 of the drawings they form a five room two story gable roof doll house, the front of which is open in order that dolls and pieces of miniature furniture may be inserted into and removed from the various rooms. They are formed of any suitable rigid material, such, for example, as plywood or stiff cardboard. Preferably the material of which the various component parts of the house are formed is $\frac{1}{8}$ " or $\frac{3}{16}$ " in thickness.

The units 10 and 11 are adapted to be assembled in side by side relation and when positioned or assembled in such relation form the first story of the doll house. The unit 10 has an open front and defines one room of the house. It is rectangular or box-like so far as configuration is concerned and consists of a floor forming bottom wall 17, inner and outer upstanding side walls 18 and 19, a back wall 20, and a ceiling forming top wall 21. These walls are suitably secured together along the abutting margins thereof in order that the unit 10 is rigid. The side and back walls are of the same height in order that the ceiling forming top wall 21 is disposed in parallel relation with the floor forming bottom wall 17. The width of the unit 10 is materially greater than the height as shown in Figures 1, 2 and 9 and this is essential so far as the house as a whole is concerned. The height of the unit 10 determines the scale of the house and may vary. It is only essential that the width of the unit 10 be greater than the height. The unit 11 defines the second room of the first story of the house and is the same in depth and height as the unit 10. It consists of a floor forming bottom wall 22, inner and outer upstanding side walls 23 and 24, an upstanding back wall 25 and a ceiling forming top wall 26 and these have the abutting or adjoining margins thereof suitably secured together in order that the unit 11 is rigid. In assembling the house the unit 11 which has an open front and is of rectangular or box-like contour is positioned so that the inner side wall 23 thereof is in abutment and registering relation with the inner side wall 18 of the unit 10. When so positioned the floor forming bottom wall 22 of the unit 11 lies in the same plane as the floor forming bottom wall 17 of the unit 10 and the ceiling forming top wall 26 lies in the same plane as the ceiling forming top wall 21. The overall width of the unit 11 is slightly less than the inside height of the unit 10 in order that the unit 11 may, after being turned at right angles with respect to the unit 10, be inserted into nested relation with the unit 10, as shown in Figure 7. Preferably the unit 10 is of such width that when the unit 11 is nested into it, as shown in Figure 7,

there is a storage space between the walls 22 and 19 for storing the gable roof 16.

The units 12, 13 and 14 are adapted to be assembled in side by side relation and when positioned or assembled in such relation form the second story of the doll house. The unit 12 has an open front and defines an outside second story room. It is rectangular or box-like so far as configuration is concerned and consists of a floor 5 forming bottom wall 27, inner and outer upstanding side walls 28 and 29, an upstanding back wall 30 and a ceiling forming top wall 31. These walls are suitably secured together along the abutting margins thereof to the end that 10 the unit 12 is rigid. The side and back walls 28, 29 and 30 are of the same height in order that the ceiling forming top wall 31 is parallel to the floor forming bottom wall 27. The unit 12 is adapted to overlie and rest on the first 15 story unit 11 and is the same in width as the latter. The overall height of the second story unit 12 is slightly less than the interior or inside width of the unit 11 in order that the unit 12 may, after being turned at right angles to the 20 unit 11, be inserted into nested relation with said unit 11, as shown in Figure 6 of the drawing. The depth of the unit 12 is the same as that of the first story units 10 and 11. When the second story unit 12 is in properly assembled relation, 25 as shown in Figures 1 and 2, its inner side wall 28 lies in the same plane as the side wall 23 of the unit 11, the outer side wall 29 lies in the same plane as the outer side wall 24 and the back wall 30 lies in the same plane as the back wall 25. The overall height of the unit 13 is less than the inside width of the second story unit 12, has an open front and defines the other outside second story room of the doll house. It 30 is rectangular or box-like and consists of a floor forming bottom wall 32, upstanding inner and outer side walls 33 and 34, an upstanding back wall 35 and a ceiling forming top wall 36. The abutting or adjoining margins of these walls are suitably secured together in order that the second 35 story unit 13 is rigid. Such unit is the same in depth and height as the second story unit 12. It is adapted when properly assembled to overlie and rest on the outer portion of the ceiling forming top wall 21 of the first story unit 10. When the unit 13 is so positioned the outer side wall 34 lies in the same plane as the outer side wall 19 of the unit 10 and the back wall 35 of the unit 13 lies in the same plane as the back wall 20 of said unit 10. By reason of the fact that 40 the inside width of the unit 12 is greater than the overall height of such unit the unit 13 may, when turned at right angles to the unit 12, be nested into the latter unit as shown in Figure 5. The width of the unit 13 is materially less than 45 that of the unit 12. The second story unit 14 has an open front and is rectangular or box-like so far as configuration is concerned. It is adapted to be interposed between the units 12 and 13 and when in properly assembled relation defines 50 an open front inside second story room for the house. The depth of the second story unit 14 is the same as the depth of the main or primary second story units 12 and 13. The unit 14 consists of a floor forming bottom wall 37, upstanding side walls 38, an upstanding back wall 39, and a ceiling forming top wall 40. The adjoining or abutting margins of these walls are suitably joined or connected together in order that 55 the unit 14 is rigid. The overall width of the unit 14 is less than the inside width of the unit 60 65 70 75

13 and the overall height of the unit 14 is less than the inside height of the unit 13. As a result of this the unit 14 may be nested into the unit 13, as shown in Figure 4. Because the unit 14 is of less height than the units 12 and 13 its top wall 40 is at a lower level than the top walls 31 and 36 when the three second story units are in their operative position, and hence there is a space directly over the top wall 40, as shown or illustrated in Figure 2. The combined width of the three second story units 12, 13 and 14 corresponds to the combined width of the first story units 10 and 12.

The gable forming members 15 are in the form of isosceles triangles and serve when in place to support the gable roof 16 over the three second story room forming units 12, 13 and 14. The length of the base or lower edges of the members 15 correspond to the depth of said units. One of the gable forming members 15 is adapted to rest upon the upper outer corner of the second story unit 12 and the other member is adapted to rest on the upper outer corner of the unit 13, as best shown in Figure 2. When the two members are in properly assembled relation one overlies, and lies in the same plane as, the outer side wall 29 of the unit 12 and the other overlies, and lies in the same plane as, the outer side wall 34 of the unit 13. Horizontally elongated blocks 41 are suitably secured to the inner surfaces of the central lower marginal portions of the gable forming members 15 and serve to retain such members in their normal upright position.

The gable roof 16 comprises four rectangular sections 42, 43, 44 and 45. The sections 42 and 43 are disposed in end to end relation, as shown in Figure 1. They have the abutting margins thereof connected together by a tape variety hinge 46 and together form the front side of the roof. The other two sections, i. e., sections 44 and 45, are arranged in end to end relation and have the adjoining margins thereof connected together with tape variety hinges 47. They form the rear side of the gable roof and have the inner side margins thereof joined to the inner side margins of the sections 42 and 43 by a tape variety hinge 48. The hinges 46, 47 and 48 permit the roof 16 to be folded lengthwise and crosswise into a quarter size unit in order that it may be readily stored in the aforementioned compartment in the first story unit 10 (see Figure 9). The four sections constituting the gable roof are the same in size and are of such combined length and width that the roof when in place has end eaves which extend outwards of the gable forming members 15 and front and rear eaves which overhang the front and rear marginal portions of the top walls of the second story units 12, 13 and 14 of the house. As shown in Figures 1 and 2 the front and rear eaves or margin of the roof are of such dimensions or depth that they project beneath the ceiling forming top walls of said second story units and cover the front and rear portions of the space that is directly over the unit 14 and results from the fact that the top wall of such unit is at a lower elevation than the top walls of the second story units 12 and 13.

When it is desired to dismantle the doll house the gable roof 16 is first removed and is then folded lengthwise and crosswise. Thereafter the gable forming members 15 are removed from their normal position wherein they rest on the upper outer side corners of the second story units 12 and 13. After removal of the gable forming member 15 the room forming unit 14 is removed from

its normal position and is then slid into nested relation with the unit 13, as shown in Figure 4. After nesting the unit 14 in the unit 13 the latter is turned at right angles and is then inserted into nested relation with the unit 12, as shown in Figure 5. Thereafter the unit 12 is turned through a 90° arc and is then inserted into nested relation with the first story unit 11. After inserting the unit 12 into nested relation with the unit 11 the latter is turned at right angles, i. e., throughout a 90° arc and is then inserted into nested relation with the first story unit 10. After nesting of the five units the gable forming members 15 are inserted into the unit 14 and the folded gable roof 16 is inserted into the first story unit 10 for purposes of storing. When the house is in knock-down form it occupies but a comparatively small amount of space and hence may be readily transported or stored.

The overall width and height dimensions of the open front room forming units of a moderate sized doll house embodying the invention are as follows:

	Width	Height
	Inches	Inches
First story unit 10	15½	10
First story unit 11	9½	10
Second story unit 12	9½	9
Second story unit 13	8½	9
Second story unit 14	7	8½

The herein described doll house is essentially simple in design and is characterized by the fact that the component parts thereof may be readily assembled and dismantled. It is capable of being produced at a comparatively low cost and when in its dismantled form occupies but a comparatively small space. The assembled doll house is rigid and does not require the use of clips, fasteners or interlocking devices for holding the parts together.

The invention is not to be understood as restricted to the details set forth since these may be modified within the scope of the appended claim without departing from the spirit and scope of the invention.

Having thus described the invention what we claim as new and desire to secure by Letters Patent is:

As a new article of manufacture, a knockdown variety two story, five room, doll house comprising a pair of open front, rigid, box-like room forming units adapted to be placed in side by side and abutting relation and to form the first story of the house and each consisting of fixedly connected bottom, side, back and top walls, and three open front, rigid, box-like room forming units adapted to be placed in side by side and abutting relation and to rest on, and register with, the top walls of, the two first story units and form the second story of the house, having the same combined width as the combined width of the first story units, and each consisting of fixedly connected bottom, side, back and top walls, said two first story units being the same in height and depth, one of the first story units having its overall width less than the inside height of the other first story unit in order that when it is turned at right angles to said other unit it may be inserted into nested relation with the latter, the outer two second story units being the same in height and depth and corresponding in depth to said first story units, one of the outer second story units being the same in width as said one first

story unit, wider than it is high and of sufficiently less height than said one first story unit that when it is turned at right angles to said one first story unit it may be inserted into nested relation with the latter, the other outer second story unit being of less width than the one outer second story unit and adapted when turned at right angles to said one outer second story unit to be inserted into nested relation with the latter, the intermediate second story unit being the same in depth as the two outer second story units, of less width and height than said other outer second story unit, and adapted to be inserted into nested relation with the latter, said house also comprising a pair of similarly sized gable forming members designed and adapted to rest on, and project upwards from, the top walls of the outer two second story units, and an elongated separately formed gable roof adapted to have the ends thereof rest on, and be supported by, said gable forming members and consisting of four similarly sized rectangular, hinged together sections arranged and proportioned so that when the roof is in its proper operative position on the gable forming members the front and rear margins thereof overhang the front and rear marginal portions of the top walls of the

three second story units and cover the front and rear portions of the space that is directly over the top wall of the intermediate second story unit, and also so that in connection with dismantlement of the house the roof may be folded lengthwise and crosswise into a quarter size unit of such size that it may be inserted into said other first story unit while said one first story unit is in nested relation with the latter.
